UNITED STATES PATENT OFFICE.

GUSTAV V. KARLSON, OF ELIZABETH, NEW JERSEY, ASSIGNOR TO CHILLINGWORTH ENGINEERING CORPORATION, OF NEW YORK, N. Y., A CORPORATION OF NEW YORK.

GAS-FLAME PROTECTOR FOR FLASHERS.

Application filed March 6, 1923. Serial No. 623,100.

To all whom it may concern:

Be it known that I, GUSTAV V. KARLSON, a citizen of the United States, residing in the city of Elizabeth, in the State of New Jersey, have invented certain new and useful Improvements in Gas-Flame Protectors for Flashers, of which the following is a specification, reference being had to the accompanying drawing, forming a part 10 hereof.

This invention relates to a protector or chimney-like enclosure for a flame and is designed with particular reference to the conditions surrounding the operation of a 15 gas flame flasher in which the flame is intermittently ignited and extinguished as for signaling purposes. Under such conditions, it will be understood that the flame must be protected when burning from drafts of 20 air which might accidentally extinguish it, and secondly, the gas issuing from the burner must be supplied at all times with an adequate supply of oxygen to insure the ready ignition of the flame. These conditions 25 might readily be satisfied in a protective device or chimney-like structure designed for use with a flame which burns constantly inasmuch as the heat generated by the flame would be sufficient to insure a 30 steady outflow of heated air or products of combustion from the top of the device and a consequent inflow of fresh air to support combustion. In the case of a flashing flame which is burning only for intervals each 35 second or minute, however, the heat generated is found to be insufficient to insure a constant change of gas within any protector now known with a result that monoxides are apt to eventually envelop the flame 40 and combustion is arrested. The present invention, accordingly, is concerned with the very peculiar conditions which surround the operation of a flashing gas flame and must be considered with particular reference to 45 such conditions in determining the importance of the results secured.

In accordance with the invention it is proposed to provide a transparent flame protector which shall prevent the flame from 50 being subjected to gusts or drafts which might extinguish it and, at the same time, insure the constant replenishing of the air or gas within the protective device with adequate oxygen to support combustion. The 55 invention rests, in principle, on the provi-

sion of parts in such relation as to effect a thermo-siphon action to the end that air within the device of somewhat rare density is constantly displaced by fresh cool air of greater density so that constant circulation 60 in and about the burner is brought about.

For an understanding of one practical embodiment which illustrates the principle, reference is to be had to the accompanying drawing, wherein:

Figure 1 is a view in plan of the improved device.

Figure 2 is a view in vertical section but showing the burner in elevation.

While the invention is not to be closely limited to its uses it has been designed primarily with reference to the conditions encountered in the art of gas flame flashers as now in use for signaling purposes, not only in light-houses but for highway traffic. In 70 such flashers alternative periods of light and darkness are effected constantly and automatically to the end that a signal effect is produced. However, it is, of course, necessary to protect the pilot flame when burning from gusts or drafts which might accidentally extinguish it. Further, it is equally necessary to provide the flame at all times with an adequate supply of oxygen to support combustion. The heat generated by 75 such a flame is comparatively slight inasmuch as the period of light is small even as compared with the period of darkness. In accordance with the present invention the burner *a* is enclosed by a tubular transparent casing *b* of glass or the like which may be carried on a metal bottom *c* supported by the base *a'* of the burner. It has been found impractical in a protector of 80 this sort to admit air from the bottom or from any point in proximity to the burner as gusts are apt to extinguish the flame accidentally when the air is so admitted. On the other hand, it has been found that the amount of heat generated by the flame is 85 ordinarily insufficient to insure a constant circulation of air within an enclosed protective device by a truly thermo-siphon action in the absence of a construction which will bring this about. The principal object 90 of the present invention is to provide such a construction. On the upper edge of the tubular casing *b* is supported a top *d* with which is carried centrally a vertical chimney *e* the lower portion of which may be 95

100 105 110

flared to spread over the top of the burner *a* and collect products of combustion therefrom. Openings *e'* at the outer end of the chimney *e* permit such gases to escape freely 5 into the atmosphere although weather devices including an annular guide *f* and cap *f'* may be supported over and around the exposed end of the chimney *e* to exclude rain, snow and the like in the manner which 10 will be apparent. In the top *d* are formed an annular series of holes *d'* for the admission of fresh air into the casing *b*. The air thus admitted is required to pass a labyrinth in reaching the interior of the casing *b* proper and an annular labyrinth is constructed so that the air will course downwardly along the inner wall of the casing *b* in an annular stream for traveling to the 15 burner *a*. To secure this an annular baffle *g* of generally conical form is supported within the top *d* so that air entering the holes will be deflected upwardly in an annular stream. In spaced relationship to the 20 conical baffle *g* is disposed a second bell-shaped baffle *h* which extends downwardly and outwardly from the chimney *e* and terminates at a point below the upper edge of the first named baffle *g* but in spaced relationship thereto so that the stream of air deflected 25 upwardly by the baffle *g* upon coursing towards the chamber *b* will be deflected downwardly and outwardly by the baffle *h* in an annular stream and follow the inner wall of the casing *b* before traveling to the 30 burner *a*. The annular stream of cold air thus introduced into the protector *b* is of relatively great density and will travel to the bottom plate *c* before altering its direction to any substantial extent. Having 35 reached the imperforate bottom *c* it will naturally course inwardly towards the burner *a* which is disposed axially of the casing *b*. The flame given by the burner *a* will be of comparatively short duration 40 and so will not generate an appreciable amount of heat. However, since the chim- 45

ney *e* is disposed directly above the burner *a* the products of combustion therefrom will naturally be trapped by the chimney for discharge in the atmosphere through the 50 openings *e'* and as these products move upwardly they will be continually displaced by the stream of fresh air introduced in the manner hereinbefore described. The important result obtained is that monoxides are 55 not trapped within the casing *b* but a continuous circulation therein is brought about to the end that combustion may be effectively supported at all times without danger of the flame being extinguished accidentally 60 by direct gusts or drafts.

Modifications in form, dimensions and arrangement of parts within limits may be made without departing from the spirit of the invention provided the described conditions are realized.

What I claim is:

In a lantern, a gas flame protector for flashers including imperforate bottom and side walls, a top supported above said side walls and extending upwardly and inwardly and having a plurality of openings adjacent the lower edge thereof, a burner disposed centrally of the protector, a duct communicating with the atmosphere, supported centrally of the top over the burner, an upwardly inclined baffle mounted in juxtaposition to the openings in the top against which all the air entering through the openings impinges and is deflected upwardly 70 against the top, a baffle supported centrally of said top extending downwardly and outwardly to a point below the upper edge of said first named baffle against which the air flowing along the top impinges and is deflected downwardly along the side walls, and an annular guide and cap enclosing the 75 openings of the duct.

This specification signed this 5th day of March A. D. 1923.

GUSTAV V. KARLSON.
